UNITED STATES PATENT OFFICE.

SAMUEL HENSHALL, OF PHILADELPHIA, PENNSYLVANIA.

MACHINE FOR SEWING LOOPED FABRICS.

SPECIFICATION forming part of Letters Patent No. 586,518, dated July 13, 1897.

Application filed April 19, 1893. Serial No. 471,027. (No model.)

To all whom it may concern:

Be it known that I, SAMUEL HENSHALL, a citizen of the United States, residing in Philadelphia, Pennsylvania, have invented certain 5 Improvements in Machines for Uniting Knitted Webs, of which the following is a specification.

My invention consists of certain improvements in that class of machines known as 10 "looping-machines" which are employed for uniting, by means of a line of stitches, two or more knitted webs which are applied to grooved pins or points carried by an intermittently-moving plate, the needle which carries the looping-thread being vibrated across 15 said plate and being guided by the points through the successive stitches of the courses of knitted web applied to said points, so that the stitches formed by the action of the needle and looper or other equivalent stitch-forming mechanism serve to unite together 20 said courses of knitted loops.

One object of my invention is to so construct 25 a machine of this class as to provide simple and efficient means for forming, alternately in and out of the work, the successive stitches resulting from the joint action of the needle and looper, so as to form what is known as a 30 "double-stitch" seam—that is to say, one in which only every other stitch engages with the loops of knitted web—such a seam possessing greater elasticity than a single-stitch seam in which the successive uniting stitches engage with successive loops of the courses 35 of knitted web which are to be united.

A further object is to so hang the looper-arm as to prevent excessive stretching of the 40 stitches formed by the joint action of the needle and looper.

These objects I attain in the manner hereinafter set forth, reference being had to the accompanying drawings, in which—

Figure 1 is an end view of sufficient of a 45 looping-machine to illustrate my present invention, part of the work-carrying plate being shown in section. Fig. 2 is a plan view with the tension-carrier arm in section. Fig. 3 is a sectional view of part of the machine. Fig. 4 is a plan view of the looper and looper-arm. Fig. 5 is an enlarged sectional view of part 50 of the machine, and Fig. 6 is a view illustrating a modification of part of the invention.

1 represents a bed-plate, from which projects upward and outward an arm 2, in which is formed a bearing for the driving-shaft 3, the latter having an eccentric 4, a duplex cam 5, and an eccentric-ring 6.

Secured to and projecting from the arm 2 is a stud 7, on which is free to turn a sleeve 8, and on the latter are mounted a spur-wheel 9 and a cam 10, secured together, the spur-wheel meshing with a pinion 11 on the driving-shaft 3, so that said wheel 9 will make one rotation for every two rotations of the driving-shaft.

The sleeve 8 passes through an elongated slot 12 in an arm 13, which is thus at liberty both to swing around the axis of the stud 7 and also to move longitudinally in respect to said stud, and said arm 13 carries at its lower end a curved needle 14 and has upon its inner side an antifriction-roller 15, which bears against the face of the cam 10, the upper end of the arm 13 being acted upon by a spring 16, tending to constantly lift said arm and thus maintain its roller 15 in contact with the face of the cam. It will be evident, however, that in place of the cam 10 and spring 16 a disk having a cam-slot in its face for the reception of the roller 15 might be employed in order to move the needle-arm positively in both directions. (See Fig. 6.)

The sleeve 8 carries in advance of the arm 13 a bell-crank lever 17, one arm of which fits between ribs or flanges 18 on the arm 13 and is secured to the latter by means of confining-screws 19, one of which passes through a slot 20 in the lever-arm and screws into the arm 13, while the other screw 19 passes through a slot 21 in the arm 13 and screws into the lever-arm. While the needle-arm is thus compelled to vibrate with the lever 17, it is free to move longitudinally independent of said lever under the influence of the cam 10 and spring 16. Hence on one vibration the needle-arm may be depressed, so as to cause its needle to work close down to a grooved point 22 of the rotating plate or carrier 23 and thus pass through the loops or courses of knitted web carried by said point, while on the next 95 vibrating movement the needle-arm may be lifted, so as to permit its needle to swing above the work and thus, by coöperation with the looper-hook 24, form first a stitch uniting 100

the loops of the fabric and then a stitch outside of said loops, so as to give the seam the desired elasticity.

It should be understood that the plate 23 is intermittently operated, as usual, by pawl and-ratchet mechanism actuated by the eccentric 4, so as to present the points 22 in succession to every other movement of the needle.

10 The vibration of the lever 17 is effected by means of the eccentric-ring 6, with which engages a shoe 25, hung to the short arm of said lever, so as to be free to swing thereon.

If it is desired to use the machine for single-stitch work only—that is to say, work in which the successive stitches are formed through successive loops of the knitted fabric applied to the points 22—the needle-arm 13 may either be drawn down to the full extent and secured 20 in this position by tightening the screws 19 or the cam 10 may be disconnected from the wheel 9 and moved to such position as to permanently depress the arm 13, the speed of movement of the plate 23 being increased, so 25 as to present a new point 22 on each vibration of the needle.

The looper-hook 24 has a compound or four-motion swing imparted to it by means of the duplex cam 5, which comprises a peripheral 30 portion 26 and a side cam 27, the peripheral cam acting upon a lug 28 on the looper-arm 29 and the side cam acting upon a lug 30 on said arm, the pivoting of the arm with reference to this compound movement being 35 effected by hanging the forked inner end of the arm by means of a horizontal pin 31 to the head 32 of a swivel-bolt adapted to a bearing 33 on the bed-plate 1.

A spring 34 tends to lift the looper-hook and 40 also to draw the same sidewise, so as to hold the lugs 28 and 30 in contact with the cams 26 and 27.

It will be observed on reference to Fig. 4 that the forked or pivot end of the looper-arm 45 29 is laterally offset on the same side of the arm from which the looper-hook projects, so that the axis upon which the looper-arm swings is substantially in line with the acting portion of said hook. Hence the latter swings 50 in an arc, such as indicated by dotted lines, which is as close as possible to the work hanging upon the points 22, the acting portion of the hook being at its opposite extremes of movement substantially equidistant from the point 55 22, carrying the loops which are being joined, as shown by dotted lines in Fig. 4. Hence there is no excessive draft upon the needle-thread and no pulling of long stitches, as would be the case if the looper-hook moved in such 60 an arc as to cause it to travel away from the work in catching the loop of needle-thread and retaining the same on the withdrawal of the needle. Consequently the take-up is very slight and a very light tension can be employed, which conduces to the formation of an elastic seam.

It will be noticed on reference to Fig. 1 that

the point 22 has an offset 35, so that that portion of the point which receives the work is in a higher plane than the portion resting 70 upon the ring 23.

In order to secure the points laterally in position, they are let into recesses in the plate and the intervening metal is flattened down over the points, as shown in Fig. 5. 75

Where the projecting portion of the point is in the same plane as the portion thus secured to the plate, therefore, it sometimes happens that the needle strikes the metal which secures the point and is bent or broken 80 thereby, an objection which, it will be evident, is effectually overcome when the work-holding portion of the point is in a plane above that which rests upon the plate, so that the needle in its movement never approaches 85 closely to that portion of the point which is secured to the plate.

Having thus described my invention, I claim and desire to secure by Letters Patent—

1. The combination in a looping-machine, of an intermittently-rotated disk having projecting points to which the loops of the webs to be united are applied, a vibrating lever, an arm mounted upon the same so as to be capable of sliding toward and from the axis of vibration of the lever, a needle so mounted upon said arm that it will move in a plane parallel with the loop-holding points, a cam which serves to move the needle-arm away 95 from the axis of vibration of the vibrating lever, and means for maintaining an engaging element of said arm in contact with said cam, substantially as specified.

2. The combination in a looping-machine, 105 of an intermittently-rotated disk having projecting points to which the loops of the webs to be united are applied, a vibrating lever, an arm mounted upon the same so as to be capable of sliding toward and from the axis of vibration of the lever, a needle so mounted upon said arm that it will move in a plane parallel with the loop-holding points, a cam acting upon said needle-arm and serving to move the same away from the axis of vibration 115 of the vibrating lever, and a spring acting upon said needle-arm and serving to move it in the opposite direction, substantially as specified.

3. The combination in a looping-machine, 120 of an intermittently-rotated disk having projecting points to which the loops of the webs to be united are applied, a pivoted lever, a shaft having means for vibrating said lever, an arm mounted upon the vibrating lever so 125 as to be capable of sliding toward and from the axis of vibration of the same, a needle so mounted upon said arm that it will move in a plane parallel with the loop-holding points, a cam whereby the arm can be moved away 130 from the axis of vibration of the vibrating lever, a shaft carrying said cam, gearing whereby said shaft is turned at one-half of the speed of the shaft which operates the vi-

brating lever, and means whereby an engaging element of the arm is maintained in contact with the cam, substantially as specified.

4. The combination in a looping-machine, 5 of a circular disk having radial projecting points to which the loops of the webs to be united are applied, a vibrating needle, a looper-hook, an arm carrying the same and having at the rear a projecting lug with a 10 vertical pivotal bearing, and means for operating said parts, the looper and the pivot-lug projecting from the same side of the looper-arm, and the looper-hook, the axis of the looper-arm and the work-holding point which

carries the loops that are being joined being 15 in the same transverse plane, so that the acting portion of the looper-hook is, at its opposite extremes of movement, substantially equidistant from the point carrying the loops which are being joined, substantially as specified. 20

In testimony whereof I have signed my name to this specification in the presence of two subscribing witnesses.

SAML. HENSHALL.

JOSEPH H. KLEIN.

Correction in Letters Patent No. 586,518.

It is hereby certified that Letters Patent No. 586,518, issued July 13, 1897, upon the application of Samuel Henshall, of Philadelphia, Pennsylvania, for an improvement in "Machines for Sewing Looped Fabrics," was erroneously granted to said Samuel Henshall, whereas said Letters Patent should have been granted to *Anna K. Henshall, as executrix of said Samuel Henshall, deceased*; and that the said Letters Patent should be read with this correction therein that the same may conform to the record of the case in the Patent Office.

Signed, countersigned, and sealed this 20th day of July, A. D. 1897.

[SEAL.]

WEBSTER DAVIS,
Assistant Secretary of the Interior.
